UNITED STATES PATENT OFFICE.

BERT CARLISLE, OF SANTA ANA, CALIFORNIA.

AUTOMATICALLY-LOCKING HAIRPIN.

1,357,271.

Specification of Letters Patent. Patented Nov. 2, 1920.

Application filed May 22, 1919. Serial No. 298,930.

To all whom it may concern:

Be it known that I, BERT CARLISLE, a citizen of the United States, residing at Santa Ana, in the county of Orange and State of California, have invented new and useful Improvements in Automatically-Locking Hairpins, of which the following is a specification.

My object is to make an improved hair pin, and my invention consists of the novel features herein shown, described and claimed.

Figure 1 is a view in elevation of a hair pin embodying the principles of my invention as seen looking in the direction indicated by the arrow 1 in Fig. 2.

Fig. 2 is a view in elevation at right angles to Fig. 1 as indicated by the arrow 2 in Fig. 1.

Figs. 3, 4 and 5 are perspectives illustrating operations of the hair pin.

The hair pin is constructed of hard spring wire and comprises the legs 1 and 2 extending from opposite ends of the coil 3. The hair pin is made of a single piece of wire and the coil 3 is at the center of the piece and consists of substantially one and a half turns. The legs 1 and 2 are substantially mates.

The coil 3 is bent far enough so that the legs 1 and 2 cross substantially at their centers and at the crossing point 4 the legs press together, and at the ends 5 and 6 the legs are spread apart, so that when the hair pin is inserted into the hair a quantity of

hair will pass between the points 5 and 6, and continued insertion of the hair pin will cause a rotary motion until the wisp 7 of hair which passed between the points 5 and 6 lies in the space 8 adjacent to the coil 3 and at the opposite side of the crossing point 4 from the points 5 and 6.

In order to remove the hair pin from the hair it is necessary to overcome the tension of the wire and press the legs 1 and 2 apart until the wisp of hair 7 will pass the point 4.

The legs 1 and 2 are perfectly smooth and straight, and the hair pin depends entirely upon the tension of the wire for its gripping quality.

When it is desired to manually remove the hair pin from the hair the coil 3 is grasped and turned a quarter turn and then the legs 1 and 2 assume parallel positions wide enough apart for the wisp of hair to pass freely between the legs.

Various changes may be made without departing from the spirit of my invention as claimed.

I claim:

A hair pin formed of hard spring wire comprising a central coil of substantially a turn and a half, and straight legs extending from the ends of said coil across each other, said coil maintaining said legs in spring contact with each other at their crossing point.

In testimony whereof I have signed my name to this specification.

BERT CARLISLE.
